UNITED STATES PATENT OFFICE.

ANTON J. HAUG, OF NASHUA, NEW HAMPSHIRE, ASSIGNOR TO IMPROVED PAPER MACHINERY COMPANY, OF NASHUA, NEW HAMPSHIRE, A CORPORATION OF MAINE.

METHOD OF AND APPARATUS FOR WORKING PAPER STOCK.

Application filed November 21, 1919. Serial No. 339,565.

To all whom it may concern:

Be it known that I, ANTON J. HAUG, a citizen of the United States, and a resident of Nashua, county of Hillsborough, and 5 State of New Hampshire, have invented an Improvement in Methods of and Apparatus for Working Paper Stock, of which the following description, in connection with the accompanying drawings, is a specification, 10 like characters on the drawings representing like parts.

This invention relates to methods of and apparatus for working paper stock and has for its object the provision of improved 15 methods and appliances which may be employed in preparing crude pulp from raw material or in working the crude pulp to a more refined state or in working over the tailings or residue from screened stock and 20 rendering it usable.

The invention will best be understood by reference to the following description when taken in connection with the accompanying 25 illustration of one specific embodiment thereof, while its scope will be more particularly pointed out in the appended claims.

In the drawings:—

Figure 1 is an elevation, principally in 30 longitudinal section, showing a machine embodying one form of the invention;

Fig. 2 is a transverse, sectional elevation taken on the line 2—2 in Fig. 1 and looking in the direction of the arrows thereon; and

Fig. 3 is a similar sectional elevation 35 taken on the line 3—3 in Fig. 1 and looking in the direction of the arrows thereon.

Referring to the drawings and to the embodiment of the invention therein illustrated, I have shown the same exemplified in 40 a machine of the general type or class illustrated in my prior Patent No. 1,302,469, dated April 29, 1919, and intended primarily for refining crude pulp and especially tailings or rejections from a prior screening 45 operation, although the same principles and substantially the same mechanism and appliances may be usefully employed in reducing raw materials to the form of a crude pulp, the machine being capable of useful 50 employment in connection with materials

(herein generally termed paper stock) of widely different condition such, for example, as more or less unreduced fibrous material, or pulp reduced to a more or less crude state.

55

Referring first to the general characteristics of the machine illustrated in the drawings, the same includes a body or casing herein in the form of a cylindrical shell 1 carried by suitable supports 2 which rest upon the bed plate or frame 3. The casing is herein fixed but the same might have a movement of rotation either with or without the bodily movement of the rolls hereininafter referred to. A casting or housing 4 secured to one end of the casing contains within it an inlet chamber to which the stock may be introduced through a suitable inlet passage herein leading from an overhead hopper or feed device 5. The stock 60 is progressively advanced from the inlet chamber through the casing to a discharge chamber 6, the latter formed within the casting or casing 7 secured to the opposite end of the cylindrical shell 1, there being 65 provided a discharge passage at the bottom and at one side of the outlet chamber 6 through the discharge pipe or conduit 8 (Figs. 2 and 3).

On its movement through the casing the 70 stock is subjected to a succession of reducing actions by some crushing agency, preferably by the means of rolls. While various devices may be employed for this purpose, herein there are provided one or more 75 rolls 10 extending lengthwise the cylinder and adapted to bear against the stock distributed over the inner face of the cylinder, the rolls being carried around the inside of the cylinder by suitable supports so that 80 they are caused to move bodily in a closed orbital path and roll over and crush the stock in their movements. While any number of rolls and rolls of any desired shape 85 may be employed, herein four similar rolls 90 10 are utilized, arranged ninety degrees apart. These rolls and their supports and driving mechanism are substantially similar and the working parts for one roll only need be described. The rolls each have at 95 10

their opposite ends journal shafts 11 which are mounted to turn in journal boxes 12 carried by revolving spiders 13 and 14. Each spider is keyed to the main drive shaft 15, 5 the latter being mounted in the fixed bearings 16 and 17 at opposite ends of the machine and being provided at one end with the driving pulley 18. The journal boxes for opposite ends of each roller are each 10 connected by connections hereinafter described to their respective spiders so that they are adapted to move radially outward or inward in suitable guides. The result is that as the spiders 13 and 14 are rotated by 15 the driving shaft, the rolls are forced into contact with the stock which is distributed over and traveling across the inner surface of the cylindrical shell, such forcible outward movement of the rolls being effected 20 either by centrifugal action or the action of suitable springs, or both. When centrifugal force is mainly relied upon, as herein, the pressure increases with the speed of the machine so that the reducing action of 25 the machine may be to some extent regulated by varying the speed.

The machine as illustrated is preferably continuously fed, the stock being continuously fed through the inlet hopper 5 and 30 continuously delivered through the outlet chamber 6. In order progressively to advance the stock through the machine between each reducing action of the successive rolls, suitable feeding devices are 35 preferably employed. These may be of any desired and appropriate type but herein I have shown secured to the driving shaft a series of devices which form, in effect, a mechanical screw conveyor acting 40 to convey the material from one end of the machine to the other while subjecting it to the repeated reducing action of the rolls. Such conveyor devices herein are provided in the form of inclined or helical vanes 20 45 suitably cut away to avoid interferences with the rolls 10. These vanes are formed in units, each unit being mounted on a hub 21 and the hubs non-rotatably secured to the driving shaft 15. Such a screw conveyor 50 extends longitudinally the drum, beyond the effective portions of the rolls into the inlet chamber so that, as soon as the stock is delivered to the latter, it becomes subject to the conveying action of the conveying devices. 55 At the opposite end of the machine in the outlet chamber 6, blades or paddles 22 are provided, secured to the spider 14, the blades or paddles rotating within the chamber and tending to work the material therein out 60 through the discharge conduit 8. The spider 14 carries a flange 23 which overlies the open end of the discharge chamber so as to prevent the escape of the refined stock therefrom except as it passes out through 65 the conduit 8.

The action of the machine so far as described will be readily understood. The stock on entering the cylinder is subjected to the crushing and reducing action of one of the rolls. Emerging from beneath the first 70 roll, it is engaged by the approaching part of a conveyor vane 20 which acts not only progressively to advance the material lengthwise the cylinder before delivery to the next roll, but also to scrape up and agitate 75 the material in its flattened sheet-like form and heap it up in front of the next approaching roll in the form of a relatively thickened mass. The material is then again rolled and crushed by the next adjacent roll 80 and the same action is repeated over and over again, to wit, the reduction of the material by the one roll and its progressive conveyance through a predetermined distance lengthwise the cylinder before its succeeding engagement by the next roll. The conveying devices progressively advance the stock between successive reducing actions 85 lengthwise the rolls, so that the same stock meets the same roll at an advanced position 90 lengthwise the machine. Not only may there be maintained an even distribution of the stock over the inner surface of the cylinder, but all portions of the stock fed through the apparatus may be subjected 95 substantially to the same reducing actions, which latter may be predetermined in amount.

In machines of this class where the material is subjected to the crushing action produced by a rolling agency such as the rolls 10, if the frictional contact of the roll upon the material is relied upon to turn the rolls, the roll may at times tend to slip or slide over some of the stock, particularly where 105 the roll meets a thickened mass of stock or a bundle of fibres of different consistency from that of the body of stock. Since the consistency of the material, the amount of material fed and the uniformity of 110 the feed cannot be maintained exactly the same at all times, the extent of this slipping action cannot be governed or predetermined and the reducing or refining action of the apparatus upon the fibres may become more 115 or less indeterminate and more or less ineffective. It has also been found desirable to cause a slight, uniform and predetermined slip between the crushing or rolling agency and the material acted upon, so as to produce 120 a drawing action on the fibres, such drawing action being found of assistance in reducing the slivers.

The prevention of an excessive, irregular and indeterminate slip may be secured by 125 positively driving the rolls as they pass over the stock which is presented by the inner surface of the cylinder. By positively driving the rolls, furthermore, at a slightly greater or lesser speed than the speed they 130

would have if turned wholly by a true rolling contact with the stock, a constant, uniform and predetermined slip may be had and the slight drawing action referred to 5 may be produced so that the reducing action results from a combination of the rolling and drawing actions.

While the rolls, if desired, may be driven faster than the natural speed which they 10 would have if driven by true rolling contact with the stock, thus getting a forward slip or draw, preferably they are driven at a slower speed, thus producing a backward slip or draw. In the described embodiment 15 of the invention, therefore, driving means are provided for positively turning the rolls at the same time that they are bodily carried around the cylinder by the spiders 13 and 14. Furthermore, the driving gearing 20 is so designed that the rolls are driven at a lesser speed than they would acquire if driven by a true rolling contact against the amount of stock which, under normal operating conditions of the apparatus and 25 under normal and predetermined conditions of feed, would be distributed over the interior of the cylinder, thus causing them to roll over the stock but with the slight backward slip or draw.

30 If the rolls are designed to turn more slowly than the speed at which they would be driven by rolling contact over a circumferential path corresponding to the path determined by the normal quantity of pulp 35 in the cylinder, then, when the machine is being driven without the presence of pulp between the rolls and the cylinder, if the rolls are brought into contact with the cylinder they will turn with an excessive 40 amount of slip with relation to the cylinder walls since they are traveling over a circumferential path greater than that normally presented by the stock. To avoid objectionable frictional wear which might result 45 from the idle operation of the machine under such circumstances, such provision is preferably made that while the rolls may be forced outwardly by centrifugal force against the pulp while the latter is being 50 fed through the cylinder, a limit is provided for this outward movement, so that, under normal conditions, when there is no pulp in the machine, a clearance is maintained between the rolls and the inner 55 surface of the drum, this keeping the rolls out of contact with the drum. This clearance may be relatively small so that the effective 60 action of the rolls against the stock when the latter is introduced into the drum is in no wise impaired.

While some unyielding limiting means might be utilized to limit the outward movement of the rolls, herein yieldable limiting devices are employed in the form 65 of heavy springs which limit the outward

movement of the rolls. These springs are preferably so adjusted that they normally maintain the clearance between the rolls and the drum but relieve the bearings of each roll from the effect of shocks which 70 might arise from a sudden outward jump of the roll occurring, for example, from the passage of the roll over a large or thickened mass of stock or over knots or other obstructions which would force the rolls inwardly and then permit them to move quickly outward.

Referring now to the details of construction which provide for the conditions herein above referred to, each journal box 12 80 is mounted in trunnions 30 (see Fig. 3) which are supported in a bearing yoke 31, the latter adapted to slide in parallel guides 32, four sets of such parallel guides being carried by each one of the spiders 13 and 14. As the spiders rotate and the rolls move round the interior of the drum, the bearing yokes tend to move outward in the guides under centrifugal action, the rolls being thus forced against the stock on the inner 90 surface of the drum. When the machine is at rest or slowed down, the rolls are prevented from dropping by means of the springs 33 each of which is seated between an appropriate projection on the bearing 95 yoke and a similar projection on the hub of the spider. These springs may be utilized to assist centrifugal action in forcing the rolls against the drum or may be relatively light and strong enough only to take 100 the weight of the rolls.

To yieldably limit the outward movement of the rolls, the outer wall of each bearing box for each end of the roll, when in its outward position with the machine operating at its normal speed, is brought into contact with the head of a stud 34 which is supported by the spider and so located that it maintains the required clearance between the roll and the inner surface of the shell. 110 The head of the stud rests against a heavy spring 35 contained within the spring box 36, the latter fixedly secured (Fig. 3) to the guide arms 32 of the spider. The end of the stud is threaded and carries a washer 115 with adjusting nuts 37, so that the head of the stud cannot move inwardly beyond a certain, predetermined, adjustable position. The spring being designed of sufficient strength, this definitely limits the position 120 of the roll under normal working conditions, affording the desired clearance. At the same time the stud is adapted to yield slightly under any sudden abnormal outward thrust so that the resulting shock is 125 taken off from the bearings and taken up by the stock on the inner surface of the drum or by the drum if stock is absent.

To lubricate the bearing boxes 12, the latter are provided with oil passages 40 which 130

extend radially with relation to the drive shaft and face small oiling devices 41 arranged around the periphery of an oil chamber contained within the annular sleeve or casing 42, the latter being bolted to the spider at 43—43 etc. (See Fig. 3.)

Any suitable means may be employed to positively turn the rolls but herein each roll shaft 11 carries at each opposite end a pinion 50, the pinions at one end meshing with the teeth of an internal gear 51 and at the opposite end with the teeth of a similar gear 52. The gear member 51 is bolted to a casing 53 which is secured to the inlet end 15 of the main shell or drum and encloses the bearing parts for the rolls and their driving gearing. At the opposite end the gearing member 52 is enclosed within a similar casing 54 which is secured to the end of the 20 outlet chamber casing 7 and encloses the bearings and driving gearing for the opposite ends of the rolls. The dimensions of the internal gears and their cooperating pinions are selected to give the desired turning 25 movement of the rolls which will produce the backward slip referred to; and the teeth of the gearing are so designed in accordance with the well understood principles of gearing as to permit the necessary 30 inward and outward movement of the rolls and their driving pinions in relation to the internal driving gear without affecting the operative driving relation thereof.

The effectiveness of the refining or reducing action is substantially increased by a constant and uniform feed of stock having a substantially uniform consistency. In order to assist the uniformity of feed, the hopper 5 near its delivery end may be provided with means such as the rotary feeding device 60 carrying the radial projecting feeding fingers 61 which assist in the delivery of the stock to the inlet chamber and also in the checking of any tendency toward an excess delivery as well as assisting in breaking up any thick masses or bunches of stock. The rotary feed device is mounted transversely (see Fig. 2) the hopper and carries at its outer end the beveled gear 62 which meshes with a corresponding gear (not shown) driven by the pulley 63 which, in turn, may be driven by a belt (not shown) from the pulley 64 on the main drive shaft. The fingers on the rotary feed device constitute stock feeding and separating devices and may cooperate with other members such as the fingers 65 (see Fig. 2) projecting from the stationary guide plate 66. The guide plate 66 lies closely adjacent one side 55 of the hopper and is connected by the pin 67 working in a slot in the side of the hopper, with arms 68 at opposite ends of the rock shaft 69. The rock shaft 69 is secured to the end lever 70, the latter having a latch and cooperating quadrant 71 by which it may be

moved to different angular positions, thereby adjusting the plate up or down in the hopper and causing the stationary fingers 65 to enter to a greater or less extent between the rotary teeth 61 on the feeding device or 70 to be withdrawn beyond their circumferential path, if desired. By means of the adjustable plate 66, the rate of feed may be regulated within certain limits.

The connections of the rolls to the bearing yokes 31 permit the rolls to tip slightly, as may be required, relatively to an axis of the machine so that the rolls can adapt themselves to inequalities or unevenness in the stock and particularly to take care of the 80 coarser condition of the stock at the inlet end.

It will be obvious that in the broad aspect of the invention various other agencies and appliances may be employed for producing 85 the crushing and the rolling action herein described and that the invention is not limited to the number, form or construction of the crushing agencies or the shape or arrangement of the body or casing of the apparatus or to the respective location of the crushing agencies or their relative or actual movements, but that various modifications in the form and arrangement of parts may be employed without departing from the 95 spirit of the invention.

Claims:

1. In a machine for working paper stock or other material, the combination with a stock-receiving surface of one or more rolls, 100 means for moving each roll bodily over the stock upon said surface and means for positively turning the roll while in contact with the stock.

2. In a machine for working paper stock 105 or other material, the combination with a stock-receiving surface of a roll, means for moving the roll bodily over the stock upon said surface, means for positively turning the roll as it contacts with the stock and 110 means for progressively advancing the stock on the surface.

3. In a machine for working paper stock or other material, the combination with a stock-receiving surface of a roll, means for 115 moving the roll bodily over the stock upon said surface, means for positively turning the roll as it contacts with the stock and means for progressively advancing the stock on the surface lengthwise the roll.

4. In a machine for working paper stock, the combination with a cylindrical casing of one or more rolls extending lengthwise the casing, means for repeatedly presenting paper stock to the same roll in said casing 125 but at different, progressively advanced points in its length, means for moving the roll bodily around the casing and means for positively turning the roll as it is moved.

5. A machine for working paper stock or 130

- other material wherein the material is fed continuously to the machine inlet and withdrawn from the outlet thereof, characterized by the employment of one or more crushing 5 rolls moved in an orbital path within the machine and driving means for positively turning each roll as it is moved.
6. In a machine for reducing materials, the combination with a materials-receiving 10 surface of rolling devices to subject the material thereon to successive crushings, means for moving said rolling means bodily over said surface, means for positively turning said rolling means and independent feeding 15 means to advance the material on said surface between successive crushings.
7. In a machine for working paper stock or other material, the combination with a materials-receiving surface of one or more 20 rolls, means for moving the rolls bodily over the stock upon said surface and means for positively driving the rolls at a speed different from that corresponding to the speed determined by true rolling contact 25 with the stock.
8. In a machine for working paper stock or other material, the combination with a materials-receiving casing of a roll, means for moving said roll in an orbital path over 30 the stock upon the surface of said casing and means for turning the roll while so moved to provide a predetermined slip with relation to the stock.
9. In an apparatus for working paper 35 stock or other material, the combination with a materials-receiving surface of a roll and means for moving said roll in an orbital path relatively over the material with a predetermined slip.
- 40 10. A machine for working paper stock having a cylindrical casing, a roll adapted to be moved around the casing in contact with the stock contained on the surface thereof, means for imparting to said roll in its movement a predetermined slip with relation to the material.
11. The method of working paper stock which consists in moving a rolling agency in an orbital path over the stock and causing 50 the rolling agency to slip with relation to the stock.
12. The method of working paper stock which consists in moving a rolling agency in an orbital path over the stock and causing 55 the rolling agency to slip backward with relation to the stock.
13. A machine for working paper stock having a casing, one or more rolls within the casing, bearings for each of said rolls, means 60 for moving the bearings to carry the rolls in an orbital path within the casing and means to positively turn the rolls in their movement.
14. In a machine for working paper stock, 65 the combination with a casing of one or more rolls, supports or bearings therefor for carrying said rolls in an orbital path within the casing and while in contact with stock therein, and means to turn the rolls while so moved at a speed less than the speed 70 which would be determined by rolling contact with the stock.
15. In a machine for working paper stock, the combination with a cylindrical shell having an inlet and an outlet of one or 75 more rolls extending lengthwise the shell and in working proximity to the inner surface thereof, supports for the rolls, means to move the supports relatively to the shell to produce relative movement between the rolls 80 and the stock in the cylinder, means for positively turning said rolls at a speed different from that determined by rolling contact with the stock and conveying devices to advance the stock from the inlet toward the 85 outlet.
16. In a machine for working paper stock, the combination with a materials-receiving surface of one or more rolls mounted in working proximity to said surface, means 90 for causing bodily rolling movement between the rolls and the surface transversely the latter, devices for positively turning the rolls at a speed different from that determined by rolling contact with the material 95 and conveying means to convey the stock between successive rolling actions lengthwise of the surface.
17. In a machine for working paper stock, the combination with a cylindrical casing of 100 one or more rolls with supporting means therefor on which said rolls are adapted to travel through an orbital path through the interior of said casing, said rolls being supported to permit a radial inward and outward movement under variations in centrifugal force and means for positively turning said rolls during their movement.
18. In a machine for working paper stock, the combination with a cylindrical casing 110 having an inlet and an outlet of one or more rolls within said casing, rotary supporting means for said rolls adapted to rotate about an axis coinciding with the axis of the casing while supporting said rolls at one 115 side of said axis, guides upon said supporting means to permit inward and outward movement of said rolls and driving gearing for positively turning said rolls in their movement.
19. In a machine for working paper stock, the combination with a cylindrical casing having an inlet and an outlet of one or more rolls within said casing, rotary supporting means for said rolls adapted to rotate about 120 an axis coinciding with the axis of the casing while supporting said rolls at one side of said axis, guides upon said supporting means to permit inward and outward movement of said rolls, driving gearing for posi- 125
14. In a machine for working paper stock, 65 the combination with a casing of one or more rolls, supports or bearings therefor for carrying said rolls in an orbital path within the casing and while in contact with stock therein, and means to turn the rolls while so moved at a speed less than the speed 70 which would be determined by rolling contact with the stock.

- tively turning said rolls in their movement and means for positively limiting the outward movement of the rolls.
20. In a machine for working paper stock, 5 a casing, one or more rolls within the casing, a journal box for each opposite end of each roll, a rotary support carrying radial guides for each journal box, a driving pinion for each roll and a driving gear engaging said 10 pinion.
21. In a stock-working machine, the combination with a cylinder of a roll adapted to move in working proximity to the inner surface of the cylinder and supported to permit 15 a radial inward and outward movement and means for limiting the outward movement of the roll to provide a clearance between the same and the inner surface of the cylinder.
20. 22. In a machine for working paper stock, a cylinder, a roll adapted to move in working proximity to the surface thereof and supported to permit a radial inward and 25 outward movement of the roll and means to yieldably limit the outward movement of the roll.
23. A machine for working paper stock having a casing provided with an inlet and an outlet, stock-crushing means within the 30 casing, feeding means to convey the stock from the inlet to the outlet between each successive crushing action and means to regulate the delivery of stock to the inlet end of the machine.
35. 24. A machine for working paper stock having a casing provided with an inlet chamber and a discharge chamber, one or more rolls within the casing to subject the stock to successive rolling actions, feeding 40 devices to convey the stock step by step from one end of the casing to the other and feeding devices also within said inlet and discharge chambers.
25. A machine for working paper stock having a casing provided with an inlet and 45 an outlet, means within the casing to subject the stock to alternate crushing and conveying actions and separating devices at the inlet to separate the stock feed thereto.
26. In a machine for reducing or refining 50 paper stock, the combination with rolling means of feeding means and a rotary stock-separating device having radial projections located at the inlet end of the machine in the path of the incoming stock.
27. In a machine for reducing or refining 55 paper stock, the combination with rolling means of feeding means, a movable device having projecting members designed to act upon the incoming stock and an adjustable stationary member having projections adapted to cooperate with the projections on the movable member.
28. In a machine for reducing or refining 60 paper stock in combination with a casing of one or more rolls adapted to be moved within said casing, each roll being mounted in journals to permit tipping movement lengthwise its axis.
29. In a machine for working paper 65 stock, the combination with the casing of one or more rolls working within the casing, a rotary support for moving said rolls within the casing, journals for each roll and a connection between each journal and its rotary support permitting tipping movement of the roll.
- In testimony whereof, I have signed my name to this specification.
- ANTON J. HAUG.
